Specification for Design.

Patented Nov. 19, 1918.

Application filed September 6, 1918. Serial No. 252,980. Term of patent 14 years.

To all whom it may concern:

Be it known that I, ALEXANDER TURNER, a subject of the King of Great Britain, and a resident of Edinburgh, Midlothian, Scotland, have invented a new, original, and ornamental Design for Golf-Balls, of which the following is a specification, reference being had to the accompanying drawing, forming a part thereof.

Figure 1 is an elevation of a golf ball embodying my design. Fig. 2 is a view at right angles to that shown in Fig. 1.

I claim:

The ornamental design for a golf ball, as shown.

ALEXANDER TURNER.
